UNITED STATES PATENT OFFICE

148,411

DESIGN FOR AN ATOMIZER SPRAY ATTACH-
MENT FOR A CONTAINERSamuel Gimelli, Berne, Switzerland, assignor to
Drugs Limited, London, EnglandApplication May 29, 1946, Serial No. 130,223
In Great Britain December 3, 1945

Term of patent 7 years

(Cl. D83—1)

To all whom it may concern:

Be it known that I, Samuel Gimelli, a Swiss citizen, residing at Beaulieustr 6, Berne, Switzerland, have invented a new, original, and ornamental Design for an Atomizer Spray Attachment for a Container, of which the following is a specification, reference being had to the accompanying drawing, forming part thereof.

Figure 1 is a front perspective view,
Figure 2 a rear perspective view,

Figure 3 a front view, and

Figure 4 is a rear elevational view of an atomizer spray attachment for a container, showing my new design.

I claim:

The ornamental design for an atomizer spray attachment for a container, as shown.

SAMUEL GIMELLI.
